SUPPORTING AND WEIGHING DEVICE
Herbert W. Link, 8330 Sorrento, Detroit, Mich.
Filed Apr. 1, 1963, Ser. No. 269,376
10 Claims. (Cl. 177—208)

This invention relates to a supporting and weighing device, and more particularly to improvements in devices of this type.

The present invention relates more especially to improvements in the type of device shown in the patent to Weber Number 2,956,761, dated October 18, 1960.

Devices of this type comprise a platform upon which the load is supported and fluid pressure means for supporting the platform, the fluid pressure being controlled by a pilot valve actuated by changes in the load, to maintain the platform at a constant level.

In devices of this type the platform moves vertically with respect to its supporting structure in response to changes in the load, and in use is apt to become tilted or canted and bind on its support and thus deleteriously affect its operation of the pilot valve.

It is therefore a primary object of this invention to provide a device of this type having improved means for transmitting the movement of the platform to the pilot valve so that any tilting or canting of the platform will not affect the operation of the pilot valve.

Another object is to provide a device of this type in which the connection between the platform and the pilot valve actuating mechanism comprises a point contact whereby if the platform tilts it will rock about this point contact and not disalign the remainder of the pilot valve actuating mechanism.

The objects and advantages of this invention are accomplished by a simple but effective mechanism which comprises a supporting or guide rod or extension on the platform depending perpendicularly therefrom and having a point contact with a vertically movable plunger, laterally supported by a bearing member, such as a series of ball bearings. The plunger engages one end of an arm or lever pivotally supported intermediate its length for rocking movement. The other end of the arm or lever activates the pilot valve. Thus any tilting movement of the platform takes place about the point contact and will not affect the operation of the rest of the pilot valve actuating mechanism.

The various objects and advantages, and the novel details of construction of one commercially practical embodiment of the invention will become more apparent as this description proceeds, especially when considered in connection with the accompanying drawings, in which:

FIGURE 1 is a longitudinal vertical sectional view through a supporting and weighing device constructed in accordance with the invention;

FIGURE 2 is a fragmentary sectional view taken substantially on the plane indicated by line 2—2 in FIGURE 1, this view being on a smaller scale and partly in elevation; and

FIGURE 3 is a detail sectional view taken substantially on the plane indicated by line 3—3 in FIGURE 2.

The device of this invention consists essentially of a base plate 10, a load supporting platform 11, a reservoir 12, a center support 13 for the load supporting platform, a pilot valve 14 for controlling the supply of air to the reservoir 12 and a rockable arm or lever 15 for transmitting the vertical movement of the platform to a movable part of the pilot valve 14.

The load supporting platform 11 consists of a top plate 20 provided with an annular depending flange 21 which defines the outer wall of an air chamber 22.

The inner wall of the air chamber 22 is formed by a

2

wall 23 of the reservoir which is in the form of an inverted substantially doughnut-shaped member. The outer edge of the wall 23 of the reservoir 12 engages an annular upwardly extending wall 24 formed on the base plate 10 and the inner wall of the reservoir engages an upwardly extending central sleeve-like portion or wall 25 extending upwardly from the base 10. The outer and inner edges of the wall 23 of the reservoir are sealed to the elements 24 and 25.

As described in the aforesaid patent, restricted communication is established between the reservoir 12 and the chamber 22 by means of a restricted opening 26 formed in the wall of the reservoir.

The space between the wall 23 of the reservoir and the annular flange 21 of the load supporting platform is sealed at the lower end thereof by means of a hollow tubular sealing ring 30 formed of a suitable plastic or other elastomeric material. The space between the inner wall 23a of the reservoir and a centrally arranged depending extension 31 on the load supporting platform 11 is also sealed by a hollow tubular sealing ring 32. The normal diameter of the sealing rings 30 and 32 is greater than the distance between the adjacent walls which they engage so that these annular rings are substantially flattened when inserted. Therefore, as the load supporting platform moves up and down, the sealing rings 30 and 32 roll along the opposed surfaces to effectively seal the space between the reservoir and the load supporting platform.

The centrally arranged extension 31 is in the form of a supporting stud or rod and is rigidly connected to the load supporting platform and extends perpendicularly therefrom in a downward direction. The end of this rod or extension 31 is provided with a semispherical element or rounded button-like member 35 so as to provide a point contact with a vertically movable plunger, yet to be described. Thus, irrespective of any tilting movement of the load supporting platform 11, this movement will not be transmitted to the plunger and will not cause a binding of the parts which operate the pilot valve 14.

Arranged within the sleeve-like portion or wall 25 is a bearing sleeve 36, and located within the bearing sleeve is a bearing cage 37 having spaced sets of ball bearings 38 arranged in two rows each with the balls of one row being circumferentially staggered with respect to the balls of the adjacent row. Arranged within the bearing gauge is a plunger 39. It will be noted that with the ball bearings arranged in sets spaced longitudinally of the plunger 39, these bearings provide lateral support for the plunger while permitting frictionless longitudinal movement thereof.

The upper end of the plunger 39 is in engagement with the semispherical member 35 and, as stated, has a point contact therewith which will not be affected by any tilting movement of the load supporting platform 11. The lower end of the plunger 39 engages one end 40 of the rockable arm or lever 15. The other end of the lever is provided with an adjustable stud 41 adapted to engage and actuate a movable part of the pilot valve 14, yet to be described.

The rockable arm or lever 15 is pivoted intermediate its length on a knife edge bearing 42 which engages a V-shaped recess 43 formed in the underside of the rockable lever 15. The rockable lever 15 operates in a cutaway portion 44 formed in the base plate 10. The knife edge bearing member 42, see FIGURES 2 and 3, is provided with laterally extending ears or lugs 45 and the bearing member 42 with its lugs 45 is inserted in a cutaway portion 46 formed transversely of the base plate 10 and is secured to the base plate by means of fastening elements 47; see particularly FIGURES 2 and 3.

The load supporting platform 11 is guided in its vertical movement by means of laterally extending lugs 50, each provided with an aperture 51 which engages an adjustable

member 52 secured to the base plate 10; see the left-hand side of FIGURE 1.

The pilot valve shown at the right-hand side of FIGURE 1 is substantially the same in its operation as the pilot valve shown and described in the aforesaid patent. It consists of a housing 60 provided with a valve stem 61 having a valve part 62 adapted to normally close a port 63 interposed in an air inlet 64. The valve also comprises a plunger 65 (heretofore referred to as the movable part of the pilot valve) provided with an exhaust passage 66. Air is permitted to exhaust from the interior of the housing 60 through an exhaust passage 67 extending through a screw 68 arranged in a removable plug 69 in the side wall of the housing.

The plunger 65 is connected to a diaphragm 70 which extends across the valve housing 60 to define a chamber 71. This chamber is connected by ports or passages 72 and 73 to the reservoir 12. The exhaust passage 66 is normally closed by the end 74 of the valve stem 61. A spring 75 normally urges the valve stem 61 to closed position. The adjustable stud 41 on the rockable lever 15 engages the end of the plunger 65 to actuate the latter.

When the load on the load supporting platform increases, the rod or extension 31 will move the plunger 39 downwardly and rock the rockable lever 15 so that the stud 41 thereon will raise the plunger 65 and thus open the inlet port 63 to permit an additional supply of air under pressure to flow through the chamber 71, and through ports 72 and 73 into the reservoir to counteract the increase in the load. When, however, the load is lightened and the load supporting platform rises above its normal level, the air in the chamber 71 will, through the diaphragm 70, lower the plunger 65 and open the exhaust port 66 to permit air to escape from the reservoir so that the load supporting platform will return to its normal position.

The pressure of air in the system may be measured by a gauging device 80 connected by a conduit 81 to the passageway 72. The dial of the gauge is preferably calibrated to indicate in pounds the load placed upon the load supporting platform.

No claim is made herein to the pilot valve 14 or to the measuring device 80, as they form no part of this invention.

It will be understood from the foregoing that if the load supporting platform 11 is tilted or canted, during operation of the device, due to the fact that the load is not placed squarely on the center of the platform, it will make no difference because the load supporting platform will rock about the semispherical element 35 and thus maintain a line contact with the plunger 39. Thus, the plunger 39 and the rockable lever 15 will not be deleteriously affected by any tilting movement of the platform whereby the movable valve part is always properly actuated in response to any movement of the platform. Thus, the structure described heretofore provides a simple but effective means for accurately actuating the pilot valve under all conditions of operation.

While a commercially practical embodiment of the invention has been described and illustrated herein somewhat in detail, it will be understood that various changes may be made as may come within the purview of the accompanying claims.

What is claimed is:

1. In a device of the class described, a vertically movable load supporting platform, a centrally arranged extension on said platform, a vertically guided plunger, means providing a point contact between said extension and plunger, a pilot valve having a movable part, and an arm pivotally supported intermediate its length for rocking movement engaging said plunger and the movable part of the pilot valve for transmitting the vertical movement of said platform to said movable valve part.

2. In a device of the class described, a vertically movable load supporting platform having a centrally arranged

supporting rod depending therefrom, a vertically guided plunger, rounded means forming a point contact between said supporting rod and plunger, a pilot valve having a movable part, and a rockable arm pivotally supported intermediate its length for transmitting the movement of said plunger to said movable valve part.

3. In a device of the class described, a vertically movable load supporting platform having a centrally arranged supporting rod depending therefrom, a plunger, antifriction bearing for mounting said plunger for vertical movement, means providing a point contact between the adjacent ends of said supporting rod and plunger, a pilot valve having a movable part, and a rockably supported arm having one end engaging said plunger and the other end engaging said movable valve part for transmitting the vertical movement of said platform to said movable valve part.

4. In a supporting and weighing device comprising, a base plate, a reservoir secured to said base plate, a vertically movable load supporting platform having a portion arranged in spaced telescopic relation with said reservoir and forming a chamber therebetween, and a pilot valve having a movable part for controlling air pressure in said chamber, that improvement which comprises, a centrally arranged depending extension on said platform, a plunger having antifriction bearing for mounting said plunger for vertical movement, means providing a point contact between the adjacent ends of said extension and plunger, and a rockable arm pivotally supported intermediate its length and having its ends engaging respectively said plunger and movable valve part for transmitting the vertical movement of said platform to said movable valve part.

5. A device as described in claim 4 in which the means providing the point contact consists of a semispherical element carried by the end of said extension.

6. In a supporting and weighing device comprising, a base plate, a reservoir secured to said base plate, a vertically movable load supporting platform having a portion arranged in spaced telescopic relation with said reservoir and forming a chamber therebetween, and a pilot valve having a movable part for controlling air pressure in said chamber, that improvement which comprises, a supporting rod rigidly secured to said platform and extending perpendicularly therefrom in a downward direction, a plunger, means for mounting said plunger for vertical movement comprising a bearing sleeve carried by said reservoir in spaced relation to said plunger and a cylindrical bearing cage in the space between said plunger and bearing sleeve having sets of bearing elements located adjacent the ends thereof, and a rockable arm pivotally supported intermediate its length and having its ends engaging respectively said plunger and movable valve part for transmitting the vertical movement of said platform to said movable valve part.

7. A device as described in claim 4 in which the end of the rockable arm engaging the movable valve part is provided with an adjustable stud.

8. A device as described in claim 4 in which the pivotal support for the rockable arm consists of a knife edge bearing engaging a V-shaped recess in the rockable arm.

9. In a device of a class described, a base, a vertical movable load-supporting platform, means for sealing said platform to said base to form an air chamber, valve means on said base, means in said valve means for controlling the flow of fluid to and from said air chamber, and a rockable lever connected to said valve and to said platform in a manner to have the movement of the platform transferred to said valve to control the pressure in the chamber relative to the change in load on the platform which produced its movement.

10. In a device of a class described, a base, a vertical movable load-supporting platform, means for sealing said platform to said base to form an air chamber, valve means on said base, means in said valve means for controlling the flow of fluid to and from said air chamber, and a

rockable lever connected to said valve and to said platform in a manner to have the movement of the platform transferred to said valve to control the pressure in the chamber relative to the change in load on the platform which produced its movement, said lever engaging the center of 5 said platform and said valve means.
